UNITED STATES PATENT OFFICE

FRANK L. YETTER, OF PHILADELPHIA, PENNSYLVANIA, ASSIGNOR TO C. H. WHEELER
MANUFACTURING COMPANY, OF PHILADELPHIA, PENNSYLVANIA, A CORPORATION
OF PENNSYLVANIA

SUPPORT STRUCTURE FOR CONDENSER TUBES

Application filed November 18, 1930. Serial No. 496,377.

My invention relates to surface condensers, and particularly to that type in which the tubes are connected with or attached to the tube sheets in such way that bending or dis-
5 alignment of the tubes tends to open the joint between them and the tube sheets with resultant leakage.

In accordance with my invention, there is provided for the condenser tubes a support structure or plate through which the condenser tubes extend, and which is yieldingly or movably mounted within the condenser shell or housing, to cause or permit, upon expansion or contraction of the tubes due to 10 temperature changes, the tubes to bend in such direction and to such extent as to minimize tendency of the joints between the tubes and their sheets to open or become displaced, with resultant leakage through the tube 15 sheets around the tubes.

Further in accordance with my invention, the supporting structure or plate may be divided into a plurality of sections, yieldingly or movably mounted as aforesaid, and 20 yieldingly connected to or biased with respect to each other.

Further in accordance with my invention, two or more tube supporting structures or plates may be utilized, suitably spaced from 25 each other between the tube sheets; and more particularly, there may be utilized also a further fixed tube supporting plate disposed within the condenser shell at a suitable point between the tube sheets, or at a suit- 30 able point between the aforesaid tube supporting structures or plates.

My invention resides in features of structure and arrangement as hereinafter described and claimed.

For an understanding of my invention, and for an illustration of some of the various forms it may take, reference is to be had to the accompanying drawings, in which:

Fig. 1 is a vertical sectional view, partly 45 in elevation, of a condenser shell within which is disposed the tube supporting structure or plate.

Fig. 2 is an elevational view of one of the tube supporting plates, looking in the direction of the arrows 2, Fig. 1.

Fig. 3 is a diagrammatic view of a condenser, partly in horizontal section and partly in plan, on the line 3—3 of Fig. 1, illustrating an application of my invention.

Fig. 4 is a fragmentary sectional view 55 showing a rolled joint between a condenser tube and its tube sheet.

Fig. 5 is a vertical sectional view, partly in elevation, of a condenser shell within which is disposed a modified form of a tube 60 supporting structure.

Referring to Figs. 1 and 3, C is the shell of a surface condenser, having at a suitable region in its length an upwardly extending portion 1 having the large port 2 through 65 which enters the exhaust steam or other vapor to be condensed.

As usual, the steam or vapor passes between and around the many tubes *t* extending longitudinally in the shell, parallel to each other, and in number largely filling the cross 70 section of the shell.

At the ends of the shell, as indicated in Fig. 3, are the cooling water boxes B, B1, between which and the interior of the shell 75 are as usual the tube sheets T, T through which the several tubes *t* connect with the water boxes.

The connection of each tube *t* to the tube sheet T may be of various types. However, 80 the present invention is principally, though not exclusively, concerned with that type of connection in which there is little or no movement as between the tubes and the tube sheet upon expansion or contraction of the tubes. 85 In general, the type of connection more particularly referred to may be styled a rigid or fixed connection. For example, and preferably, the type of connection is such as illustrated in Fig. 4, where each tube *t* extends 90 through an aperture in the tube sheet T.

The aperture is enlarged somewhat as indicated at *a*, and the tube is rolled in the region indicated at *b* into firm or substantially rigid engagement with the sheet T 95 forming a fluid-tight joint.

In the operation of a surface condenser the tubes *t* are compelled to partake of considerable changes in temperature due to different operating conditions and due to mischances. 100

For example, if the supply of cooling medium fails or decreases, the tube *t* will rise in temperature, expand in length, and tend to rupture the joint between it and the tube sheet 5 *T*. If this should occur, there may be leakage of cooling water or of air into the interior of the condenser, which is generally under 10 vacuum or subatmospheric pressure. Generally, the cooling water is water from an ordinary water supply or from the sea, and in either case, if it leaks into the interior of the condenser, it contaminates the condensate. Or, if the cooling water supply should fail 15 and air find its way into either box *B* or *B*₁, upon rupture of the joint of the tube *t* with the tube sheet *T*, air or other gaseous medium will leak into the vacuum system, disadvantageously lowering the vacuum.

In expanding under abnormally high temperature, a long tube *t* tends to buckle or become disaligned, and the shape of the tube departs from its usual or normal straight form to an irregular bend or sinuous form.

To permit the tubes *t* to expand, but nevertheless to control the deformation resulting from their expansion, confining them to a form which has minimum tendency to open the joints between the tubes and their tube sheets, I provide within the condenser shell 25 *S* a support structure for the tubes, preferably in the form of a plate or plates.

As indicated in Fig. 3, these support plates or structures are shown at *S*, *S*, in this instance two in number. Between them may 35 be provided a support structure or plate *P* fixed in its position with respect to the shell *C*, and through apertures in which the tubes extend with sliding fit.

In an arrangement such as indicated in Fig. 3, upon expansion of tubes *t* they will bow into a simple non-sinuous arc between the left hand tube sheet *T* and the plate *P*, and again between the plate *P* and the right hand tube sheet *T*, the support or plates *S* yielding or moving as the tubes bend, and confining their bends to the aforesaid simple arcuate form.

As more clearly shown in Fig. 1, the tube support structure or plates *S* are two in number in substantially the same transverse plane. They have as many apertures *c* as there are tubes *t*, which extend through these apertures with a sliding fit. Each of the plates or supports *S* has a substantially 50 straight or horizontal portion *d* at its lower end, adapted to rest and ride upon a roller *e* pivoted in a bracket *f* secured upon the bottom of the shell *C*. Each of the support plates *S* is preferably provided also with a shoulder or lug *g* resting upon a roller *h* carried in a bracket *i*, secured upon the interior of the shell *C*. On their adjacent sides the support plates *S* are provided with the brackets *j*, through which extend the rod *k* upon 55 which are threaded nuts *m* between which

and the brackets *j* are compressed the spiral springs *s*. As indicated in Fig. 1, there may be provided a plurality of pairs of these brackets and spring assemblies. The springs bias the tube support structures or plates *S* 70 toward each other; the springs *s* tend to draw the plates *S*, *S* toward each other.

As the tubes *t* expand or contract as aforesaid, they do so in generally the same way, and in unison, since they are coupled by the 75 support structures or plates *S*, which in turn, under expansive or contractive movement of the tubes, move upon their roller supports *e* and *h*, thereby yielding or moving with respect to the shell *C*.

The supporting plate structure in fact controls the expansion and contraction of the tubes in such way as to minimize their tendency to become loosened at their joints in the tube sheets *T*. The springs *s* are adjusted to such compressional tension that they move the supports *S* slightly, but nevertheless sufficiently, to cause the bend in all the tubes of each group passing through their support to be substantially in the same direction, and each to bend away from the shell in a simple arc, whereby each of the tubes will be caused to have the same degree of deflection under the influence of temperature change.

By a structure of this character, the joints of the tubes in their sheets *T* are maintained tight while nevertheless allowing the unavoidable expansion or contraction of the tubes.

While, as stated, the so-called rolled joints are preferred, it will be understood that my invention is applicable as well to situations where the joints between tubes and their tube sheets may be of several types. In general, and without limiting my invention thereto, it may be stated that my structure is applicable more particularly to condensers in which the tubes connect with their tube sheets in joints of a rigid type or those which do not employ the usual packings.

In Fig. 5 the structure is generically the same as that illustrated in Figs. 1, 2 and 3. The tube supporting structure or plate *S* is in this case unitary, as may often be the case where the condensers are of moderate or small capacity. The plate *S* again has a substantially horizontal edge at its bottom bearing upon rollers *e* carried by the bracket *f* secured upon the interior of the shell *C*. It may be provided also with the shoulder or edge *g* bearing upon the roller *h* carried by the bracket *i* secured upon the interior of the shell *C*. The plate *S* is biased toward the right by the spring *s* disposed between the nut *m* and the bracket *j* secured to the plate *S*. The nut or head *m* is adjustably mounted as in the case of Fig. 1 upon a rod *k*, which in this case is pivoted at *o* to the bracket *p* secured upon the interior of the shell *C*. In general, the operation is the same as that

above described in connection with Figs. 1, 2 and 3.

What I claim is:

1. The combination with a condenser comprising spaced tube sheets and tubes extending between said sheets and having joints therewith, of movable tube supporting structure between said tube sheets having apertures through which said tubes extend, means permitting movement of said supporting structure with said tubes, and means biasing said tube supporting structure in such direction as to cause each of the tubes to have the same degree of deflection under the influence of temperature change.
2. The combination with a condenser comprising spaced tube sheets and tubes extending between said sheets and having joints therewith, of movable tube supporting structure between said tube sheets, and means slidably supporting said supporting structure upon the condenser, and means for biasing said supporting structure in such direction as to cause each of the tubes to have the same degree of deflection under the influence of temperature change.

3. The combination with a condenser comprising spaced tube sheets and tubes extending between said sheets and having joints therewith, of tube supporting structure between said tube sheets, means slidably supporting said supporting structure upon the condenser, and means biasing said supporting structure in a direction which causes each of the tubes to have the same degree of deflection under the influence of temperature change.

4. The combination with a condenser comprising spaced tube sheets and tubes extending between said sheets and having joints therewith, of tube supporting structure between said tube sheets, and a rolling support for said supporting structure upon the condenser.

5. The combination with a condenser comprising spaced tube sheets and tubes extending between said sheets and having joints therewith, of tube supporting members disposed between said tube sheets and movably mounted upon the condenser, and a yielding connection between said members acting in such direction as to cause each of the tubes passing through said supporting members to have the same degree of deflection under the influence of temperature change.

6. The combination with a condenser comprising spaced tube sheets and tubes extending between said sheets and having joints therewith, of tube supporting members disposed between said tube sheets and movably mounted so as to travel in a straight line, and a resilient connection between said members to bias the same along their direction of travel.

7. The combination with a condenser com-

prising spaced tube sheets and tubes extending between said sheets and having joints therewith, of tube supporting plates disposed substantially in the same plane between said tube sheets and having apertures through which the tubes extend, and means for movably mounting said plates upon the condenser, and means for biasing said plates so that each tube will have the same amount of bias and in the same direction as each of the other tubes passing through the same supporting plate.

8. The combination with a condenser comprising spaced tube sheets and tubes extending between said sheets and having joints therewith, of tube supporting plates disposed substantially in the same plane between said tube sheets and having apertures through which the tubes extend, means for movably mounting said plates to travel in a straight line, and a yielding connection between the adjacent edges of said plates for biasing the same.

9. The combination with a condenser comprising spaced tube sheets and tubes extending between said sheets and having joints therewith, of tube supporting plates disposed substantially in the same plane between said tube sheets and having apertures through which the tubes extend, means for movably mounting said plates to move horizontally upon the condenser, and a resilient connection between the adjacent edges of said plates for biasing the same.

10. The combination with a condenser comprising spaced tube sheets and tubes extending between said sheets and having joints therewith, of a member fixed with respect to the condenser and disposed between said tube sheets and through which the tubes extend for defining a fixed point for each tube on either side of which it may bend under the influence of temperature change, and tube supporting structure between said plate and one of said tube sheets movably mounted with respect to the condenser.

11. The combination with a condenser comprising spaced tube sheets and tubes extending between said sheets and having joints therewith, of a plate fixed with respect to the condenser and disposed between said tube sheets and through which the tubes extend for defining a fixed point for each tube on either side of which it may bend under the influence of temperature change, tube supporting structures between said plate and said tube sheets on opposite sides of said plate, and means movably mounting said supporting structures upon the condenser.

12. The combination with a condenser comprising spaced tube sheets and tubes extending between said sheets and having joints therewith, of a member fixed with respect to the condenser and disposed between said tube sheets and through which the tubes ex-

tend for defining a fixed point for each tube on either side of which it may bend under the influence of temperature change, and tube supporting structure between said plate 5 and one of said tube sheets movably mounted to travel in a straight line and in a transverse direction with respect to the tubes, and means for biasing said supporting structure, whereby each of the tubes passing therethrough 10 will have the same degree of deflection under the influence of temperature change.

13. The combination with a condenser comprising spaced tube sheets and tubes extending between said sheets and having joints 15 therewith, of a plate fixed with respect to the condenser and disposed between said tube sheets and through which the tubes extend for defining a fixed point for each tube on either side of which it may bend under 20 the influence of temperature change, tube supporting structures between said plate and said tube sheets on opposite sides of said plate, and means movably mounting said supporting structures and adapted to travel in a straight line and in a transverse direction 25 with respect to the tubes, and means for biasing said supporting structures so that the tubes will have the same degree of deflection under the influence of temperature change.
